HAND GRIP FOR A MOTION PICTURE CAMERA OR SIMILAR ARTICLE

Norman R. Kubnick, Wheeling, Ill., assignor to Bell & Howell Company, Chicago, Ill., a corporation of Illinois

Filed Oct. 20, 1961, Ser. No. 67,183

Term of patent 14 years

(Cl. D61—1)

FIG. 3.

FIG. 2.

FIG. 5.

FIG. 6.

FIG. 4.

FIGURE 1 is a side elevation view of a hand grip for a motion picture camera or similar article;
FIG. 2 is a front elevation of the same;
FIG. 3 is a side elevation of the side opposite that shown in FIGURE 1;
FIGURE 4 is a rear elevation of the hand grip;
FIGURE 5 is a top view of said grip; and
FIGURE 6 is a bottom view of the same.
The broken-line showing of a camera in FIGURE 1 is for illustrative purposes only.

I claim:

The ornamental design for a hand grip for a motion picture camera or similar article, as shown and described.
